UNITED STATES PATENT OFFICE.

WILLIAM M. SPENCER, OF ERIE, PENNSYLVANIA.

DESIGN FOR A MILITARY UNIFORM.

Application filed July 9, 1924. Serial No. 10,102. Term of patent 3½ years.

To all whom it may concern:

Be it known that I, WILLIAM M. SPENCER, a citizen of the United States, residing at Erie, in the county of Erie, and State of Pennsylvania, have invented a new, original, and ornamental Design for Military Uniform, of which the following is a specification, reference being had to the accompanying drawing, forming part thereof.

The figure is a front view of a military uniform, showing my new design.

I claim:

The ornamental design for a military uniform, as shown.

WILLIAM M. SPENCER.
